US00D938470S

(12) **United States Design Patent** (10) Patent No.: **US D938,470 S**
(45) Date of Patent: **** Dec. 14, 2021**

(54) **DISPLAY PANEL WITH A GRAPHICAL USER INTERFACE**

(71) Applicant: **LINE Plus Corporation**, Seongnam-si (KR)

(72) Inventors: **Eunsun Hwang**, Seongnam-si (KR); **Eun-Joon Lee**, Seongnam-si (KR); **Jeong Yub Lee**, Seongnam-si (KR)

(73) Assignee: **LINE PLUS CORPORATION**, Gyeonggi-do (KR)

(**) Term: **15 Years**

(21) Appl. No.: **29/733,278**

(22) Filed: **Apr. 30, 2020**

(30) **Foreign Application Priority Data**

Nov. 1, 2019 (KR) 30-2019-0052059

(57) **CLAIM**

The ornamental design for a display panel with a graphical user interface, as shown and described.

DESCRIPTION

The single FIGURE is a front view of a display panel with a graphical user interface (GUI) showing a new design. The broken lines in the FIGURE showing the display panel and portions of the graphical user interface form no part of the claimed design.

1 Claim, 1 Drawing Sheet
